C. M. STROUD

OIL BURNER

Filed Sept. 4, 1924

FIG. 1

FIG. 3

FIG. 2

INVENTOR
CHARLES M. STROUD

By Paul, Paul & Moore
ATTORNEYS

UNITED STATES PATENT OFFICE.

CHARLES M. STROUD, OF MINNEAPOLIS, MINNESOTA.

OIL BURNER.

Application filed September 4, 1924. Serial No. 735,867.

To all whom it may concern:

Be it known that I, CHARLES M. STROUD, a citizen of the United States, resident of Minneapolis, county of Hennepin, and State of Minnesota, have invented certain new and useful Improvements in Oil Burners, of which the following is a specification.

This invention relates to new and useful improvements in oil burners, and more particularly to such oil burners adapted for use in connection with steam or hot water boilers or hot air furnaces such as are employed for heating houses and other buildings. The construction of this novel burner is such that it will readily lend itself for use in conjunction with the usual coal-burning furnace, the necessary changes to convert such a furnace to a liquid fuel burning furnace being practically minimized.

20 The particular object of this invention, therefore, is to provide an improved oil burner of simple and inexpensive construction, which may readily and quickly be installed in any ordinary coal-burning furnace 25 for the purpose of converting such a furnace to a liquid fuel burning furnace.

A further and more specific object of the invention is to provide an oil burner having a cone-shaped member which has its outer 30 upper surface spirally rifled so as to cause the liquid fuel, discharged from the apex of said member, to follow a tortuous path as it downwardly flows thereover, thereby to more thoroughly break it up before combustion.

Other objects of the invention will appear from the following detailed description and the accompanying drawings and will be pointed out in the annexed claims.

40 In the drawings there has been disclosed a structure designed to carry out the various objects of the invention, but it is to be understood that the invention is not confined to the exact features shown as various changes 45 may be made in the scope of the claims which follow.

In the drawings:

Figure 1 is a sectional view of the novel oil burner;

50 Figure 2 is a plan view of the base of the burner showing the central opening therein through which air is supplied to the burner; and

55 Figure 3 is a plan view of the cone-shaped member of the burner showing the spiral

ridge thereon for retarding the flow of fuel as it downwardly flows thereover.

In the selected embodiment of the invention here shown there is illustrated an oil burner comprising a saucer-like burner base 60 or receptacle 4 having a central opening 5 therein formed by the upwardly turned flange 6. A hub 7 is preferably concentrically arranged within the central opening 5 and is supported by means of radial arms 65 8 as shown in Figure 2. The hub 7 is provided with an aperture 9 through which a fuel feed pipe 11 is inserted, as shown in Figure 1. The other end of this pipe is connected to a suitable source of supply 70 not shown.

A cone-shaped member 12, having a central hub 13, is seated on the hub 7 of the base and is preferably secured thereto by means of the upright portion 10 of the fuel 75 pipe 11, which, as shown in Figure 1, extends up into the hub 13 and has its end secured thereto by suitable means, not shown. An oil duct or conduit 14 upwardly leads from the fuel pipe 11 and terminates 80 at the apex of the cone-shaped member 12.

One of the features of this invention resides in the novel means provided for retarding the flow of liquid fuel as it downwardly flows over the surface of the member 85 12. Such means preferably consists in the provision of a ridge 15 arranged to encircle the major portion of the member 12 and having its convolutions arranged in the form of a spiral as shown in Figure 3. 90 An annular ridge 16 preferably concentric with the axis of the member 12 is provided adjacent the lower portion of the cone-shaped member, and this ridge functions to provide a wall to prevent the flow of liquid fuel from passing through the elongated openings 17 and into the annular combustion chamber 18 arranged to encircle the lower portion of the cone-shaped member 12. An annular groove or vaporizing chamber 19 is provided above the combustion 95

chamber 18 and is preferably formed by means of a ring 20 having an integral upturned flange 21 thereon, as shown in Figure 1. The ring 20 and upturned flange 21, 100 forming the vaporizing chamber, are preferably integrally formed with the cone-shaped member 12 by means of a plurality of short arms 22, as shown in Figure 3. The lower ridge or wall 16 is provided with 110

openings or passages 23 which communicate with a similar number of grooves 24 provided in the upper face of the arms 22 and cooperate therewith to direct the liquid fuel 5 from the lower portion of the cone-shaped member 12 to the vaporizing chamber 19. Referring to Figure 3, it will be noted that the lower terminal of the spiral ridge 15 terminates a spaced distance from the annular wall or ridge 16. Thus, when the liquid fuel is discharged from the duct 14 as indicated by the arrows in Figures 1 and 3, it will flow downwardly over the surface of the member 12 in a tortuous path, 10 thereby retarding its flow to the extent that it will be thoroughly vaporized by the time it reaches the heated vaporizing chamber 19. If desired, a small slot or passage 25 may be cut through the lower portion of 15 the ridge 15 at a point diametrically opposite from the lower terminal of the ridge 15, thereby permitting a portion of the fuel to be discharged therethrough with the result that the fuel oil will be more uniformly distributed.

Another feature of this invention resides in the means provided for causing the supply of air to the burner to follow a tortuous path, thereby causing the air to become thoroughly mixed with the vaporized fuel which will result in the formation of a highly combustible mixture which may readily be ignited, and will therefore result in efficient combustion. The means provided to effect such thorough mixing of the air and fuel resides in the provision of an annular depending flange 26 preferably integrally formed with the lower portion of the cone-shaped member 12 as particularly shown in Figure 1. This flange functions as a baffle plate to produce eddy currents by downwardly deflecting the air against the bottom of the saucer-like base 4. As the air thus downwardly and outwardly passes beneath the elongated openings 17 and the combustion chamber 18, a vacuum will tend to build up in the vaporizing chamber 19, which will result in the vaporized fuel oil being downwardly drawn through the openings 17 and into the annular combustion chamber 18 where it will be ignited and the flames outwardly jetted against the side walls of the furnace as indicated by the arrows. As the air passes beneath the lower edge of the flange 26 and through the chamber 18, a whirling action or eddy current will be imparted thereto which will result in a thorough mixing of the air and fuel oil as the vaporized fuel is downwardly drawn through the elongated openings 17 and into the chamber 18.

A cover 27 is preferably seated on the upturned flange 21 as shown in Figure 1 and this cover functions to completely enclose 45 the cone-shaped member 12 as shown. By

the employment of this cover a preheating chamber or retort 28 will be provided, which, after the burner has been started, will cause the fuel oil flowing down over the surface of the cone-shaped member 12 to become 70 thoroughly heated and vaporized. Also as a result of the vaporizing chamber 19 being located at outer portion of the cone-shaped member 12 and directly above the combustion chamber 18, the vaporizing 75 chamber will be thoroughly heated so that as the fuel oil is discharged thereinto by means of the passages 23 and grooves 24 it will become thoroughly vaporized before being drawn into the combustion chamber 80 18 through the elongated openings 17 for subsequent combustion.

I claim as my invention:

1. In an oil burner, the combination with a base having a central air opening, of a 85 cone-shaped member seated thereon, an annular vaporizing chamber encircling said member, an annular combustion chamber beneath the vaporizing chamber, and means depending from said cone-shaped member 90 adapted to downwardly deflect the flow of air against the base, thereby causing a whirling action to be imparted to the flow of air as it passes through the combustion chamber.

2. In an oil burner, the combination of a base having a central air opening, a cone-shaped member seated thereon, spiral means on said member adapted to retard the flow of fuel oil as it downwardly flows thereover, 100 a depending flange secured to the cone-shaped member adapted to downwardly deflect the air entering the burner through the central opening of the base and cause it to follow a tortuous path, an annular combustion chamber, and means enclosing said member to form a heating chamber wherein the fuel oil is vaporized before being drawn into the combustion chamber for subsequent combustion.

3. In an oil burner, the combination of a base having a central air opening, a spirally ridged cone-shaped member seated thereon, a depending annular flange secured to the cone-shaped member, a ring encircling said flange, an upturned flange secured to the ring, a cover seated on the upturned flange in spaced relation to the cone-shaped member, thereby providing a preheating and vaporizing chamber through which the 115 liquid fuel must pass before combustion.

4. A liquid fuel burner comprising in combination, a base having a central air opening, a cone-shaped member supported thereby, spiral means on said member to 125 retard the flow of fuel oil thereover, an annular combustion chamber, a ring having an upturned flange thereon secured to the cone-shaped member in spaced relation thereto, means for enclosing said member to provide 130

- a preheating and vaporizing chamber, a depending annular flange secured to the cone-shaped member adapted to downwardly deflect the air entering through the central opening of the base and cause it to follow a tortuous path as it passes through the combustion chamber, thereby effecting a thorough and complete mixing of the air and vaporized fuel for subsequent combustion.
5. In a combined gas generator and burner, the combination with a burner base having a central air intake opening surrounded by a flange, said flange disposed within the base member, a hollow conical gas generator mounted above said base member and spaced therefrom to provide a relatively constricted passageway between the base of the gas generator member and the burner base, said passageway in communication with the air intake opening and leading outwardly to the periphery of the burner base, said conical member having a closed vaporization chamber at its convex side, and having a circumferential channel on its concave side facing toward the base member and forming an expansion and mixing chamber intermediately of the constricted passageway, and means for delivering oil to the vaporization chamber, and from said chamber to said mixing chamber.
6. A device of the class described comprising a saucer-like receptacle, a hollow conical member concentric to and having its base spaced from the bottom of said receptacle to provide a relatively constricted passageway, said conical member having an eddy-producing flange, forming with the cone member an eddy-chamber intermediate of and opening toward said constricted passageway, a cover forming a closed chamber with the convex side of said conical member, said conical member having openings connecting said chamber with said eddy-chamber, and said receptacle having an air intake opening communicating with the interior of the conical member above said constricted passage, and means for delivering oil to the closed chamber.
7. An oil burner comprising a pair of hollow cone-shaped members, first and second, having their concavities opposingly related and with said members extending one within the other and spaced to provide a constricted passage therebetween, the first having an air intake opening extending into the concavity of the second and the second having a circumferential channel therein facing the constricted passage and further having passages leading into the channel, said channel providing an intermediate expansion and mixing chamber for air and gas, respectively received through the air intake opening and through the passages leading into the channel, and an oil de-
- livery conduit for delivering oil at the apex of the second member.
8. A device of the class described comprising a saucer-like base member having a relatively large flanged central air intake opening, a hollow conical member having its concave side opposed to the corresponding side of the base member, and having a cover at its convex side forming with that side a closed vaporization chamber, said conical member having its base spaced from the bottom of the base member, and further having a baffle flange depending from its concave side, with the lower edge of the flange disposed below the top of the air intake opening flange and spaced from that flange in a radial direction greater than the distance between the base of the conical member and bottom of the base member, said depending flange forming and defining with the wall of the conical member an annular mixing chamber, said conical member having openings establishing communication between the vaporization chamber and the mixing chamber, and a conduit for delivering oil within the vaporization chamber.
9. A device of the class described comprising a saucer-like base having a central air intake opening and an upwardly extending flange surrounding said opening, a hollow conical member within, overlying, and spaced above the base to form a delivery channel communicating with the air intake opening and outer portion of the base, and having circumferential and cross-sectionally triangular mixing channel in its bottom facing toward and communicating with the delivery channel, said conical member having openings leading from its upper surface to said mixing channel, and having a peripheral upstanding flange at its base on the convex side, and a second flange on said convex side adjacent the inner side of said openings, a conical cover overlying and spaced from the hollow conical member, for forming a closed vaporizing chamber thereabove and said member having a single continuous upstanding spiral flange leading from the apex to a point adjacent the second flange, and an oil supply pipe leading to the apex of the conical member.
10. A device of the class described, comprising a saucer-like burner base providing an outer inclined wall and having a relatively large central opening and an integral upstanding flange surrounding said opening, and a central hub integrally connected within the opening by radial arms to provide a relatively large intake passage, a hollow conical vaporizing member overlying the burner base with its lower end spaced upwardly from the bottom of the burner base but disposed below the level of the top of the flange and with the base periphery adjacent the lower end of the inclined wall.

of the burner base to form a relatively large chamber above the relatively large air intake opening, and forming a substantially horizontal and constricted circular passage leading outwardly to the lower portion of the inclined wall of the base, an eddy-producing flange depending from the bottom of the conical member within the hollow portion thereof, spaced from the intake opening flange a greater distance than the spacing of the bottom of the conical member from the base, and forming adjacent the periphery of and with the conical member a downwardly faced channel or eddy chamber for obtaining a whirling, mixing action of the vapors introduced respectively through the air intake opening and cone vapor intake, a cover overlying the conical member to form a closed vaporizing chamber thereabove, and an oil intake conduit leading to the vaporizing chamber.

11. A device of the class described comprising a base member having a central air intake opening and flange surrounding said

opening, a hollow conical gas generator member having a cover connected therewith forming with the member a closed vaporization chamber, said conical member overlying and spaced from the base member, to form a relatively narrow passage between the members, said conical member having a vapor-receiving and mixing chamber therein facing the narrow channel and forming an intermediate expansion chamber above and communicating with said narrow passage, said conical member having gas inlet openings communicating with the mixing channel and vaporization chamber, and a conduit for delivering oil to the vaporization chamber whereby in operation of the device air passing through the narrow channel is whirled into the mixing or expansion chamber on the way to the periphery of the base member.

In witness whereof, I have hereunto set my hand this 29th day of August 1924.

CHARLES M. STROUD.
